Primary Examiner—Wallace R. Burke*Assistant Examiner*—B. J. Bullock*Attorney, Agent, or Firm*—John W. Routh[57] **CLAIM**

The ornamental design for a deodorant container or the like, as shown.

DESCRIPTION

FIG. 1 is a front elevational view of a deodorant container or the like showing my new design;
 FIG. 2 is a side elevational view thereof;
 FIG. 3 is a rear elevational view thereof;
 FIG. 4 is a top plan view thereof;
 FIG. 5 is a bottom plan view thereof;
 FIG. 6 is a fragmentary sectional view taken on line 6—6 of FIG. 1 confined to the center panel thereof; and
 FIG. 7 is a fragmentary sectional view taken on line 7—7 of FIG. 1, confined to the outer edge thereof.
